TAP EXTRACTOR WITH SLIDABLY ADJUSTABLE FINGERS

George J. Miller, Windsor, Conn., assignor to The Walton
Company, Hartford, Conn.

Application May 27, 1955, Serial No. 511,581

6 Claims. (Cl. 81—90)

This invention relates to a tap extractor and more particularly to a device for extracting broken taps from threaded holes by rotating such taps within the holes.

It is commonly known that, heretofore, extractors for broken taps have been used which included a set of fingers that were insertable into the flutes of the broken tap for rotating it to extract it from the hole. In such previously known extractors, the fingers were interconnected in such a manner that they had to be inserted into their respective flutes for the same distance and, in cases where one or more of the flutes were clogged with chips or the like, the insertion of all of the fingers was limited to the distance permitted by the clogged flute and, in some of such cases, the clogged condition of the flutes resulted in an insufficient connection between the extractor and the broken tap.

In other devices, such as in the co-pending application of Kenneth W. Weeks, Serial No. 484,539, filed January 27, 1955, the extractor fingers are movable independently of each other but a separate operation is required to secure the fingers in their operative position after they have been inserted into their respective flutes of a broken tap.

It is an object of this invention, therefore, to provide an extractor for broken taps in which each of the plurality of tap engaging fingers may be extended from a holder and inserted into a flute of the broken tap independently of the other fingers, by merely moving each finger on the holder and without requiring a separate operation for securing the fingers to the holder in operative positions.

A further object of this invention is to provide such an extractor which is highly efficient in its operation and which may be economically produced by reason of its simplicity of construction.

A still further object is the provision of an extractor for broken taps having a plurality of tap engaging fingers which are constantly held connected to a holder therefor and which may be moved in said holder independently of each other with only the simple operation of moving each finger to extend its free end from the holder and into a respective flute in a broken tap until it has entered said flute for the desired distance or until movement of said free end of the finger into the flute is interrupted by a clogged or similar condition of said flute.

Further objects and advantages of this invention will be more clearly understood from the following description and from the accompanying drawings in which:

Fig. 1 is a side view of an extractor for broken taps embodying the present invention.

Fig. 2 is a top end view thereof.

Fig. 3 is a bottom end view.

Fig. 4 is a view in central vertical section on line 4—4 of Fig. 3.

Fig. 5 is a sectional end view on line 5—5 of Fig. 4.

As shown in the drawings, my improved extractor includes a holder 5 having a squared head 6 and a plurality

2

of elongated grooves 7 running longitudinally in its outer surface.

Each of said grooves is open at the bottom end of the holder 5 and has slidably mounted therein a finger 8 having a straight end portion. If desired, the said fingers may be provided with an offset grip portion 10. The number of said grooves and fingers in a holder is preferably made to correspond to the number of flutes in a tap for which the tool is intended and the diameter of the holder 5 is made to substantially conform with the root diameter of said tap.

The fingers 8 are retained in adjusted position upon the holder 5 and in their respective grooves 7 by means of a retaining sleeve 11 which is slidable over said holder and the fingers 8 therein and has a bushing 12, of rubber or other suitable resilient material, which is contained within an annular groove 13 in the wall of the axial bore of said sleeve 11 and extends for a portion of the length of said bore.

In the preferred construction of my improved extractor for broken taps, the outside surfaces of the fingers 8 are contoured to conform with the circular contour of the holder 5 and, when located in their respective grooves in said holder, the outer surfaces of said fingers are disposed upon a diameter which is slightly less than the diameter of the holder 5. The sleeve 11 has a bore of a diameter to slidably receive the holder and fingers and allow a slight clearance between the outer surfaces of the fingers and the surface of the bore to provide a tolerance for slight variations in the diameter at the outside surfaces of the fingers which will prevent binding of such fingers between the bottoms of the grooves and the wall of the bore in the sleeve and facilitate the manufacture of such tap extractors on a volume basis at a minimum cost.

The resilient bushing 12 provided by the present invention is constructed with an inside diameter that is normally slightly less than the diameter at the outside surfaces of said fingers and, when the sleeve 11 is mounted over the holder and fingers, the said bushing will become compressed between the outer surfaces of the fingers and holder and the bottom surface of the annular groove 13 and thereby firmly force the fingers 8 against the bottoms of the respective grooves 7 while also engaging with the outer surfaces of the holder 5 and frictionally retaining the said fingers in their adjusted positions relatively to the holder 5. It will be understood that the resiliency of the bushing 12 will cause portions of said bushing to reach into the grooves 7 and engage the outer surfaces of the respective fingers therein while other portions of said bushing are in engagement with the outer surfaces of the holder.

In the use of my improved extractor for broken taps, the end of the holder 5 is first placed against the end of the broken tap which is to be extracted. In cases where the end of the broken tap is inside of a hole, the said holder is inserted into the hole until it strikes the end of the tap. Each of the fingers is then separately projected from the holder and inserted into a flute of the said broken tap as far as it will enter. The sleeve 11 is then slid forwardly upon the holder, until it is positioned as close to the hole and as near to the end of the broken tap as possible, and the operation of attaching my improved extractor to the said broken tap is completed.

It will be noted from the illustration in Fig. 4 that the resilient bushing 12 extends only for a portion of the length of the bore in the sleeve 11 and that it is located adjacent the top end of the sleeve. The portion of the bore which is adjacent to the bottom end of said sleeve has a rigid wall which provides a rigid backing for each of the fingers 8 to prevent outward movement of the fingers relatively to the holder when side pressure is applied to said

fingers during the rotation of the tool in the process of extracting a broken tap.

I claim:

1. An extractor for broken taps including a holder having a plurality of grooves disposed longitudinally in its outer surface and extending to a free end thereof, a separate elongated finger member slidably mounted in each of said grooves and having an end portion adapted to be extended beyond the said free end of the holder, a sleeve surrounding said fingers and holder, and resilient means combined with said sleeve for independently retaining each of the fingers in position within its respective groove in said holder.

2. An extractor for broken taps including a holder having a plurality of longitudinally disposed grooves opening at an end thereof, a separate elongated finger member slidably contained in each of said grooves and having an end portion adapted to be extended beyond the end of the holder, a sleeve slidable over said holder and fingers, and a resilient bushing in said sleeve frictionally engaging said fingers and thereby independently retaining each finger in adjusted position in its respective groove and relatively to the holder.

3. An extractor for broken taps including a holder having a plurality of grooves disposed longitudinally in its outer surface and extending to an end thereof, a plurality of elongated fingers slidably mounted in said grooves and having free end portions extendable from the said end of the holder, the outer surfaces of said fingers when located in said grooves being disposed upon a diameter which is slightly less than the diameter of the holder, a sleeve slidable over said holder and fingers, and a resilient bushing compressed between said holder and fingers and said sleeve and normally having an inner diameter which is slightly less than said diameter at the outer surfaces of the fingers.

4. An extractor for broken taps including a holder having a plurality of elongated grooves extending longitudinally in its outer surface and extending to an end thereof, a separate elongated finger slidably mounted in each of said grooves and having a free end portion extendable from said end of the holder, each of said fingers when contained in its respective groove having its outer surfaces on a diameter which is slightly less than the diameter of the holder, a sleeve slidably mounted upon said holder and over said fingers, said sleeve having a

bore slidably receiving the holder and of a diameter providing a clearance between the inner surface of said sleeve and the outer surfaces of the fingers whereby the said sleeve is prevented from interfering with the sliding movement of the fingers in their respective grooves, and a bushing of a resilient material contained in said sleeve and extending along a portion of the length of the said bore, said bushing have an inside diameter which is normally less than the diameter at the outer surfaces of the fingers and being compressed between said holder and fingers and the inner wall of the sleeve for retaining the said holder, fingers and sleeve in adjusted position relatively to each other.

5. An extractor for broken taps including a holder having a top end, a bottom end and a plurality of elongated grooves in its outer surface opening at the bottom end of said holder, elongated fingers contained in said grooves and each adapted to be positioned for extending an end portion thereof beyond said bottom end of the holder independently of the other fingers, a sleeve slidably mounted over said holder and fingers and having a portion directly engageable by said fingers to prevent radial movement of the fingers relatively to the holder, and a resilient bushing in another portion of said sleeve engaging the said holder and fingers and yieldingly retaining them in adjusted position relatively to each other.

6. An extractor for broken taps including a holder having a plurality of elongated grooves in its outer surface extending to a free end thereof, a separate elongated finger member slidably contained in each of said grooves and having an end portion adapted to be extended to different distances from the said free end of the holder, a sleeve slidable over said holder and fingers and having an annular groove in its inner surface, and a resilient bushing contained in said annular groove and engageable with said holder and fingers for frictionally retaining the fingers against longitudinal movement in their respective grooves.
